UNITED STATES PATENT OFFICE.

JOHN MILTON JOHNSTON, OF CHICAGO, ILLINOIS.

CABINET FOR EXHIBITING EYE-TESTING DEVICES.

SPECIFICATION forming part of Letters Patent No. 728,112, dated May 12, 1903.

Application filed July 17, 1901. Serial No. 68,612. (No model.)

To all whom it may concern:

Be it known that I, JOHN MILTON JOHNSTON, a citizen of the United States, residing at Chicago, in the county of Cook and State of Illinois, have invented certain new and useful Improvements in Cabinets for Exhibiting Eye-Testing Devices, of which the following is a specification.

This invention relates to improvements in cabinets for exhibiting eye-testing devices, and has special reference to a device to be employed by opticians in ascertaining the refractive and muscular deficiencies of the eyes.

15 The main object of my invention is the provision of a cabinet for this purpose, which is very simple, durable, and inexpensive in construction and thoroughly efficient and practical in use.

20 To attain the desired objects, my invention consists of a cabinet for exhibiting eye-testing devices, embodying novel features of construction and combination of parts, substantially as disclosed herein.

25 In the drawings, Figure 1 is a front elevation of the cabinet. Fig. 2 is a vertical central sectional view thereof. Fig. 3 is a view of the device with the front removed.

Referring to the drawings, the numeral 1 designates a casing, which may be in rectangular form; but I prefer to make it in the form of a clock. Placed upon the lower front portion of this casing are the series of dots 2, the dots to the left of the center being printed in black ink and the dots to the right of the center being printed in red ink, each dot having numerals or letters or other characters 3 printed over them. The letters or figures or numerals printed over the red dots 40 are to be printed in black ink and those printed over the black dots are to be printed in red ink.

Secured to the sides 1^a of the cabinet at their front edges is a strip 2^a, provided with a central opening 2^b for the reception of the forward journal of the shaft 4. The rear end of the shaft 4 is mounted in the opening 4^a in the rear 5^a of the cabinet.

Mounted upon the shaft 4 and revolute therewith is a dial or circular disk 5, which has the index or pointer 6 revolute also therewith, said dial being observable through

the circular opening 6^a in the front of the cabinet. Placed upon the face of the casing in the segmental or semicircular recess or groove 6^b above and surrounding the upper half of the dial is the segment 7, provided with one hundred and eighty equal divisions, numbered from one to one hundred and eighty from left to right. Formed in the upper front of the case above this scale is the rectangular opening 8, through which are adapted to be seen letters or numbers carried upon a transparent belt or band 8^a, passed behind this opening by means of the rollers 65 9, which are journaled in the bearings 10 in the sides of the casing. A light 11 is employed to cause the letters to be plainly seen and may be in the casing or in any convenient position outside. I employ pulleys 12 to 70 revolve the rollers, which may be operated by the operator at any desired position. I also provide a pulley 13 upon the shaft 4 in order that the same may be revolved by the operator from any desired position.

75 From this construction it will be seen that I provide the dial generally used in testing eyes for astigmatism and the dots and figures upon the lower face of the casing for the prism test, while the revolving letters and numbers 80 will facilitate the determination of the condition of the eyes. The prism test is put into operation simply by having the patient try to observe the dots and numerals through a prism, which is placed in the patient's hand. 85 If the dots and numerals appear commingled or indistinct, the eyes are affected; otherwise they are normal.

With this device the eyes may be tested and the proper remedy may be discovered, as 90 the cause of the trouble may be readily ascertained by employing this device.

It is evident that I provide a cabinet for exhibiting eye-testing devices which is very simple, durable, and inexpensive in construction as well as thoroughly efficient and practical in use.

This cabinet has the advantage of enabling the operator to employ test-letters in single lines without confusing the patient with the presence of other tests.

What I claim, and desire to secure by Letters Patent, is—

The herein-described cabinet for eye-test-

ing devices, comprising a base, front sides, a rear wall rising therefrom, a strip connected to the sides near their front edges and opposed to the rear of the front in the lower portion of the cabinet, said front wall being provided with a rectangular opening in the upper portion thereof, a circular opening in the lower portion thereof and a segmental recess surrounding the upper circumference of the circle, a segmental strip mounted in said recess, a shaft mounted in the rear and in the strip opposed to the front of the casing and having its ends extending beyond the rear and said strip, a circular disk carried upon the

front end of said shaft and adapted to revolve within the circular opening of the front, a pair of shafts mounted in the sides in the upper portion of the cabinet, and a belt carried by said shafts and adapted to have a portion of the body thereof exposed through the rectangular opening of the front.

In testimony whereof I affix my signature in presence of two witnesses.

JOHN MILTON JOHNSTON.
